CLAIM

The ornamental design for an induction heating cooker, as shown and described.

DESCRIPTION

FIG. 1 is a front, top and right-side perspective view of a first embodiment of an induction heating cooker showing my new design;

FIG. 2 is a front view thereof;

FIG. 3 is a rear view thereof;

FIG. 4 is a top view thereof;

FIG. 5 is a bottom view thereof;

FIG. 6 is a right-side view thereof;

FIG. 7 is a left-side view thereof;

FIG. 8 is a cross-sectional view taken along line 8-8 in FIG. 2, in which an internal mechanism is omitted;

FIG. 9 is a front, top and right-side perspective view of a second embodiment of an induction heating cooker showing my new design;

FIG. 10 is a front view thereof;

FIG. 11 is a rear view thereof;

FIG. 12 is a top view thereof;

FIG. 13 is a bottom view thereof;

FIG. 14 is a right-side view thereof;

FIG. 15 is a left-side view thereof; and,

FIG. 16 is a cross-sectional view taken along line 16-16 in FIG. 10, in which an internal mechanism is omitted.

The broken lines shown represent unclaimed subject matter of the induction heating cooker and form no part of the claimed design.

(Continued)

The induction heating cooker has two controlling portions sandwiching a heating portion therebetween on an upper surface.
